UNITED STATES PATENT OFFICE.

GUSTAVE LÉON VICTOR CHAUVEAU, OF PARIS, FRANCE.

BALANCING ENGINE OR MOTOR.

SPECIFICATION forming part of Letters Patent No. 660,879, dated October 30, 1900.

Application filed June 5, 1900. Serial No. 19,125. (No model.)

To all whom it may concern:

Be it known that I, GUSTAVE LÉON VICTOR CHAUVEAU, engineer, a citizen of the French Republic, residing at 29 Rue des Belles-Feuilles, Paris, France, have invented a new and useful Improvement in Balancing Engines or Motors, of which the following is a specification.

With the object of obtaining a balanced motor or engine in which the to-and-fro motion of a piston is converted into a rotary motion and in order to avoid the vibration which is particularly inconvenient in the case of explosion-engines when applied to automobiles it has been proposed to mount two connecting-rods upon one and the same piston, each actuating a driving-shaft, the two driving-shafts being arranged in the same line and rotating in the reverse direction to one another in such a manner that two movements of equal power are obtained, which balance one another. The complete overcoming of the dead-points when two independent connecting-rods are made use of being, however, practically impossible, the two rods had to be coupled together in order to insure satisfactory working; but the means hitherto proposed for this purpose involved the use of levers, beveled gear, &c. All these means were, however, of an inconvenient nature on account of the complication and delicacy of the required construction. By the present invention I avoid these disadvantages by making use of ordinary gearing and of a counter-shaft arranged parallel to the driving-shafts. Such an arrangement allows of the counter-shaft rotating at a higher or lower speed or even at the same speed. For this reason the counter-shaft may be used for regulating the distribution in the case of an explosive-engine or the like, which has not been possible with the means formerly proposed.

In the accompanying drawings I have shown in Figures 1, 2, and 3 my invention as applied to a single-cylinder engine, Fig. 1 being a sectional front elevation; Fig. 2, a sectional side view, and Fig. 3 a sectional plan view. Fig. 4 is a sectional plan view of a modified form of a two-cylinder engine.

A, Figs. 1, 2, and 3, designates a cylinder in which moves a piston B, provided with a journal or spindle C, on which pivot the ex-

actly-similar connecting-rods D D', operating two driving-shafts E E' by means of crank-arms, which are equal. The two shafts carry each a fly-wheel H H', each provided with a weight I, counterbalancing half the piston, a connecting-rod, and a crank-arm. The two fly-wheels are similar, and the balance-weights are placed at the ends of the diameter opposite to the wrist-pin.

K and K' are two pinions operating two toothed wheels L L', which are similar, the operation of the former pinion being direct and that of the latter pinion taking place through the medium of a pinion M. The two wheels L L' are fixedly attached to the shaft N.

It will be readily understood that the to-and-fro movement of the piston is transmitted to the two driving-shafts E E', which, being connected by the gears K K' L L' M, revolve in opposite directions and at the same speed. This arrangement may be applied to any type of reciprocating engine, driven either by a fluid under pressure or by an explosive mixture or even when it is a double-acting engine, the connecting-rods in that case being no longer pivoted directly to the piston but to the rod of the latter or to intermediate parts connected to the said rod when necessary.

The fly-wheels need not be of the same form and dimensions, provided that their couples of rotation are the same. They may also be replaced by devices serving both as a fly-wheel and for the transmission of power for operating the distribution of the same either indirectly or directly, as may be desired. The whole or a part of the power may be taken from an intermediate shaft N.

The driving-shafts may be combined in some other way than that shown, be supported at more than one point, and be provided with crank-plates or disks serving as a fly-wheel, &c. Thus the cranks may be replaced by crank-shafts revolving on a central bearing between the other two, Fig. 4.

The intermediate shaft N may revolve at any speed. In explosion-motors of the four-stroke cycle type it is desirable that it should rotate at half the speed of the driving-shafts in such a manner as to allow of making use of it also for regulating the distribution, for

igniting, and other purposes. If the engine is of the two-stroke type, the counter-shaft serves the same purpose; but in that case it must of course be arranged so as to rotate at 5 the same speed as the driving-shafts.

The relation as regards the direction or the speed of the motion of the driving-shafts and that of the counter-shaft may be used for the alteration of speed or the direction, for ex- 10 ample, in autocars.

In place of a single cylinder A a series of cylinders may be employed, arranged in a circle around the driving-shafts, all their pistons being connected together by connecting- 15 rods at each crank.

The two-crank-shafts arrangement shown in Fig. 4 may also be employed, each crank-shaft corresponding in this case to a cylinder and being operated by a single connecting- 20 rod, the two shafts revolving in opposite directions, and the pistons then moving in the parallel cylinders and communicating at the top only comprising a single group of distributing devices, the cycle being the same 25 kind in both the cylinders, so that they may be considered as forming one and the same cylinder. This improved arrangement may also be applied to all motors having four, six, or eight cylinders in groups of pairs.

30 I claim—

1. The combination with two driving-shafts journaled in alinement, means to rotate said shafts in opposite directions at the same

speed, a counter-shaft, and gearing interposed between the driving-shafts and the 35 counter-shaft to transmit the movement of the former to the latter to cause its rotation, substantially as set forth.

2. The combination with two driving-shafts journaled in alinement, piston-rods connect- 40 ed to said shafts to rotate them in opposite directions, a counter-shaft, spaced gears fast on the counter-shaft, a pinion on each driving-shaft, that on one driving-shaft being meshed with one of the gears on the counter- 45 shaft, and a pinion M interposed between the other gear and the pinion, whereby the counter-shaft is driven in the same direction by both driving-shafts, substantially as set forth.

3. The combination with two driving-shafts 50 journaled in alinement, means to rotate said shafts in opposite directions at the same speed, a counter-shaft, and gearing interposed between the driving-shafts and the counter-shaft to transmit the movement of 55 the former to the latter to cause its rotation, and fly-wheels of equal couples on the driving-shafts, substantially as set forth.

In testimony whereof I have signed my name to this specification in the presence of 60 two subscribing witnesses.

GUSTAVE LÉON VICTOR CHAUVEAU.
